UNITED STATES PATENT OFFICE.

HENRY JUNGJOHANN, OF DAVENPORT, IOWA.

WICK RAISING AND LOWERING DEVICE.

1,074,868.

Specification of Letters Patent.

Patented Oct. 7, 1913.

Application filed May 1, 1913. Serial No. 784,772.

To all whom it may concern:

Be it known that I, HENRY JUNGJOHANN, a citizen of the United States of America, and resident of Davenport, Scott county, 5 Iowa, have invented a certain new and useful Improvement in Wick Raising and Lowering Devices, of which the following is a specification.

My invention relates to a device for automatically raising or lowering a wick of an 10 oil lamp or the opening or closing of a gas jet, and consists in the combination, with the lighting or extinguishing devices, of a clock mechanism by means of which the device becomes operative at any predetermined 15 hour.

The principal object of my invention consists in the attaching of an ordinary standard alarm clock to the oil burner of an oil 20 stove or heater, utilizing the usual alarm operating mechanism of the clock to manipulate the wick raising and lowering device. This I accomplish in the manner hereinafter fully described and as particularly 25 pointed out in the claims.

In the drawings: Figure 1 is a fragmentary view of an oil heater showing in elevation the base containing the burner and oil reservoir with my improved mechanism 30 in place. Fig. 2 is a vertical cross section of the same portion of the heater. Fig. 3 is a sectional view of a detail of my improved mechanism.

Similar numerals refer to similar parts 35 in the two views.

The oil heater (the lower portion only of which is shown) together with the burner and clock are of the usual construction and form no part of my invention.

To the outer end of the usual wick raising spindle 1, is secured the bevel gear 2. Supported on the shelf 3 which is securely attached to the body of the heater, are the bracket bearings 4-4^a and an ordinary alarm 45 clock 5. Spindle 6 is an extension of the usual alarm spring winding post and is supported by the bracket bearing 4-4^a and fitted with the usual winding key 6^a at its outer end. The alarm clock is so positioned 50 relative to the heater as to locate spindle 6 at right angles to and in the plane of spindle 1. Slidably mounted on spindle 6 at about its center of length, is the bevel pinion 7. Through the medium of grooves 9 and 10 in spindle 6, ball 8, spring 11 and retaining screw 12, pinion 7 can be held

into and out of engagement with gear 2. It is secured to the spindle 6 and caused to rotate therewith by the pin 13 which is rigidly fixed in the spindle with its ends extending 60 into the slots 14 in the extending hub or sleeve portion of the pinion. Thus it is seen that whether the pinion was in the position as shown in Fig. 1 with the ball 8 resting in groove 10 or moved to a position 65 with the ball engaging groove 9, the pin 13 would always engage the slot 14.

The outer face of the bevel gear 2 is provided with a series of counter-bores or holes 15 drilled partly through the web of the gear near the inner edge of the gear teeth. Clamped to the periphery of the gear 2 and locked thereto through one of the counter-bores 15 and the winged stud 16 is the limiting stop 17. This limiting stop consists of 70 a finger hold handle bifurcated at one end. One leg of the bifurcation being longer than the other and extending back of gear 2 engaging spindle 1. The other or shorter leg of the bifurcation extends over the edge and 75 face of gear 2, carrying the winged stud 16.

A pilot light 18, consisting of the small tube 19 wick 20 and the usual raising and lowering ratchet 21, is located adjacent the tube 22 of the large oil burner and so positioned as to bring the pilot flame in contact with the wick 23 of the large burner when same is raised above the edge of the tube 22 causing same to ignite. When the wick 23 is withdrawn into the tube 22, its flame will 80 be extinguished without affecting the pilot light which is always in readiness to re-light wick 23 whenever same is raised above the edge of its tube container.

After having wound up the alarm mechanism of the clock by turning the key 6^a and the sliding pinion 7 is moved into engagement with the gear 2 and automatically locked in such position by having caused ball 8 to be forced out of groove 10 and into 100 groove 9, a release of the alarm mechanism at a predetermined hour, in the usual manner, will cause spindle 6 to revolve in a direction opposite to that which it was turned on winding up of the alarm mechanism and 105 rotate pinion 7 of transmitting movement to gear 2, and will continue to rotate gear 2 until the limiting stop 17 contacts the bracket 4^a as shown in dotted lines 24. This fixed extent of movement of gear 2 will have 110 been found just sufficient to raise wick 23 to become ignited by contact with the pilot

flame and yet not too high to destroy proper combustion. When it is desired to extinguish the burner, pinion 7 is slipped out of engagement with gear 2 and wick spindle 1 is rotated backward by throwing the limiting stop 17 from the position shown in dotted lines to position shown in full line. When wick 23 burns shorter from continued use, its fixed limits of up and down travel are maintained by releasing stud 16 in limiting stop 17, advancing gear 2 sufficiently and secure stop 17 in another of the counter-bores 15.

By extending spindle 6 sufficiently and 15 slidably mounting thereon another pinion similar to pinion 7 only in a reversed position, it is seen that the wick could be lowered from a raised position at a predetermined hour just as it is raised from a lowered 20 position as herein set forth. This fixed and predetermined movement of spindle 1 by the mechanism described could also be directed to the opening or closing of a gas jet as well as to the raising and lowering of a wick.

25 What I claim as new is:

1. In combination, an oil burner, a wick, means to raise and lower said wick at a predetermined moment consisting of a spindle operated by the clock mechanism of an ordinary alarm clock and provided with a 30 slidably mounted bevel pinion, a bevel gear capable of engagement with said pinion and

provided with an adjustable stop adapted to limit the extent of movement of said gear.

2. In combination, an oil burner, brackets 35 secured to the base thereof, a spindle journaled in the free ends of said brackets, adapted to be revolved by the clock mechanism of an ordinary alarm clock, a wick raising spindle extending from said oil 40 burner and at right angles to and in the plane of the other spindle, a bevel gear on the wick raising spindle, a bevel pinion on the other spindle capable of engagement with said bevel gear, a spring actuated ball 45 engaging grooves in the spindle adapted to hold said pinion into and out of engagement with said bevel gear.

3. In a mechanism of the class described, a rotatably mounted spindle provided with 50 a bevel gear at one end, a spring actuated spindle located at right angles to and intersecting the plane of the first mentioned spindle, a pinion slidably mounted on one spindle capable of engagement with the bevel 55 gear on the other spindle, and an adjustable limiting stop co-operating with one of said gears.

Signed by me at Davenport, Iowa, this 28th day of April, 1913.

HENRY JUNGJOHANN.
